UNITED STATES PATENT OFFICE.

CLEVELAND H. QUACKENBUSH AND HARVEY E. QUACKENBUSH, OF CLEVELAND, OHIO.

ELECTRIC-LIGHT BULB.

1,425,608.

Specification of Letters Patent. Patented Aug. 15, 1922.

Application filed April 6, 1921. Serial No. 458,946.

To all whom it may concern:

Be it known that we, CLEVELAND H. QUACKENBUSH and HARVEY E. QUACKENBUSH, citizens of the United States, residing at Cleveland, in the county of Cuyahoga and State of Ohio, have invented certain new and useful improvements in Electric-Light Bulbs, of which the following is a specification.

This invention relates to electric light bulbs, more particularly to bulbs of the so-called miniature type which are generally formed from tubular glass.

In the manufacture of bulbs of this class glass tubing is generally used, the tubing being first cut into units of proper length. Globular heads are then blown, or molded on the units, said heads tapering down to a tubular neck, the neck retaining sufficient length to admit of the sealing therein, in proper position, of the filament stem. The bulbs as an article of manufacture are thus formed of predetermined uniform dimensions, and the stems are afterward sealed therein by a separate operation.

Heretofore in the manufacture of bulbs of this type, the globular head has been formed from the tubing unit while the original diametrical dimension, and thickness of material of the tube has been maintained in the neck. This uniform thickness of material makes it difficult to form a reliable seal between the neck and the filament stem.

The object of the present invention is to provide bulbs of this character that can be more expeditiously and reliably sealed than can the bulbs as heretofore manufactured. This object is attained by the peculiar formation of the bulb, which facilitates the reliable sealing, or attachment of the neck element to the stem which carries the light filament, as will be hereinafter fully described and definitely pointed out in the claims, reference being had to the accompanying drawings which are made part of the specification, similar reference characters being employed to designate corresponding elements.

In said drawings Figure 1 is an eleva-

tion of the improved bulb. Fig. 2 is a central vertical section. Fig. 3 is an illustration of a filament stem detached. Fig. 4 illustrates the improved bulb, partially in section, showing the filament stem in position for sealing, and Fig. 5 is a sectional elevation of a sealed bulb.

The present invention provides, as a new article of manufacture, a bulb having a globular element 1 formed from the tubing, 60 said globular element tapering down to the throat line 1^a where the full thickness of the material is maintained. The tubular wall of the neck is drawn down from the throat line 1^a to comparative thinness at and 65 slightly below the sealing line 1^b. This peculiar formation of the neck provides thickness of material at the throat where it is desirable for strength, while the glass being thinner at the sealing line facilitates the 70 reliable sealing of the filament stem 2 in the neck of the bulb, and the detaching of the superfluous portion 1^c of the tube, after the seal is made.

What we claim and desire to secure by 75 Letters Patent is.

1. As a new article of manufacture, an electric light bulb, comprising an inclosed head, and a tubular neck, the wall of said neck being drawn down from a predetermined thickness at the throat line to comparative thinness at the sealing line.

2. As an article of manufacture, an electric light bulb, comprising a globular head, and a tubular neck, the wall of said neck 85 being a predetermined thickness at the throat and drawn down comparatively thin in proximity to the sealing line.

3. An electric light bulb having a globular head and a tubular neck within which the filament stem is to be sealed, the wall of the neck being reduced in thickness from the head to the sealing line and increased in thickness from said sealing line to the lower terminal of the neck.

In testimony whereof we affix our signatures.

CLEVELAND H. QUACKENBUSH.
HARVEY E. QUACKENBUSH.
